US00D705069S

(12) **United States Design Patent**
Crisanti et al.

(10) **Patent No.:** **US D705,069 S**
(45) **Date of Patent:** **** May 20, 2014**

(54) **CONTAINER**

(75) Inventors: **Michael G. Crisanti**, Woodbury, CT (US); **Anne E. Nixon**, Bridgeport, CT (US); **John W. Marchese, Jr.**, Bethany, CT (US); **Reem A. Emerson**, New Brighton, CT (US)

(73) Assignee: **The Sun Products Corporation**, Wilton, CT (US)

(**) Term: **14 Years**

(21) Appl. No.: **29/406,774**

(22) Filed: **Nov. 18, 2011**

(51) **LOC (10) Cl.** 09-01
(52) **U.S. Cl.**

USPC **D9/522**; D9/523; D9/543; D9/575

(58) **Field of Classification Search**
USPC D9/516, 522-523, 530, 543, 559-560,
D9/562; 215/379, 381-384

See application file for complete search history.

(57) **CLAIM**

The ornamental design for a container, as shown and described.

DESCRIPTION

FIG. 1 is a top, front, and right side perspective view of a container showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and
FIG. 7 is a bottom plan view thereof;
FIG. 8 is a top, rear, and right side perspective view thereof; and,
FIG. 9 is bottom, rear, and right side perspective view thereof. The broken lines shown in the drawings are included for the purpose of illustrating environmental structure and form no part of the claimed design.

1 Claim, 9 Drawing Sheets
